UNITED STATES PATENT OFFICE.

CHARLES D. CROCKER, OF HARTFORD, CONNECTICUT.

AUTO SAFETY CONDUIT CUT-OFF.

1,359,035.

Specification of Letters Patent. Patented Nov. 16, 1920.

Application filed August 23, 1918. Serial No. 251,189.

To all whom it may concern:

Be it known that I, CHARLES D. CROCKER, a citizen of the United States, residing in the city of Hartford, in the county of Hartford 5 and State of Connecticut, have invented and certain new and useful Improvements in Auto-Safety-Conduit Cut-Offs, of which the following is a specification.

My invention relates to cut-off devices 10 attachable to the means of supply between the main source of supply and the point of use, and the meter in the case of illuminating or other gas, electricity, water or other fluid substance or matter with which a meter 15 is customarily employed, may be considered the point of use, and the objects of my invention are, first, to provide a cut-off device for use in a dwelling, building or other structure; which cut-off device is operated by hand in either the interior, or operated by 20 hand from the exterior of the dwelling, building or structure to shut off flow, and which also is provided with automatic operative means for shutting off flow; second, to provide such a cut-off device for use on automobiles, motor trucks and motor 25 boats; and third, to provide such a cut-off device, which when shut off by hand may readily be reset, for operation by hand or to operate automatically and which if shut off automatically may be readily and quickly 30 restored to hand operative condition.

To the accomplishment of the above stated objects, and others of a similar nature, my 35 invention consists in the construction, combination and arrangement of parts set forth in and falling within the scope of the claims forming part hereof. And it should be understood that I do not confine myself to all 40 the details of construction, as there may be modification thereof and variation therein without departing from the spirit of my invention or exceeding the scope of the appended claims:

I attain these objects by the device illustrated in the accompanying drawings in which,—

Figure 1 is a side elevation of my hand operated and automatic cut-off device applied to the inlet pipe of a building at a point between the inlet and a meter, and arranged to be shut off by hand at or near its location and also to be shut off by hand from an upper story or compartment of the 55 building, and also to be shut off by hand from the exterior of the building.

Fig. 2 is a horizontal sectional view of my cut-off device on the line 2—2 of Fig. 1.

Fig. 3 is a vertical sectional view of my cut-off device showing the means for shutting off by hand from the exterior of a 60 building.

Fig. 4 is a side view of my cut-off device.

Fig. 5 is a side elevation of my cut-off device viewed from the right hand side of 65 Fig. 4.

Fig. 6 is a plan view of Fig. 5.

Fig. 7 is a side elevation in vertical section of the valve portion of my cut-off device. 70

Fig. 8 is a view of my cut-off device as applied to an automobile, the device being attached adjacent to the carbureter.

Fig. 9 is a side view, in perspective, of a modified form of my cut-off device. 75

Fig. 10, is a top plan view, partly in horizontal section, of a modified form of my cut-off device.

Similar numerals refer to similar parts throughout the several views. My hand 80 operated and automatic cut-off device comprises, in its primary elements or parts, a valve 15, having a case, a rocker arm, 16, a vertical support 17, a horizontal support 18, and a retaining and releasing pin, 19, 85 Figs. 4, 5, 6 and 7.

The valve portion of my device consists of a valve case, 20, having an inlet, 21, attachable in the customary manner to the main supply pipe in a position between the source 90 of supply and the point of use, or as the case may be, the source of supply and the meter, tank or other gas or fluid container which, for purposes of illustration and description, may be considered the point of 95 use. The valve case 20, has a valve seat 22, in which is seated a spring operated valve, 23, having a stem 24, extending upward through the case, 20, and provided at its upper end with a pin and slot member, 25. 100

The rocker arm 16, is pivoted on the upper end of the vertical support 17, and has a recessed head, 26, the head 26, being constructed to engage in the slot of the pin and slot member, 25, of the valve stem while the 105 recess of the head, 26, engages over and plays upon the pin of the member 25. The rocker arm, 16, is of the shape shown in the drawings, that is, when in locked position, Fig. 4, it has a diagonally extending portion 27, and a downwardly and vertically extending portion, 28, the central longitu-

5 dinal line of the portion, 28, being substantially parallel with the central longitudinal line of the vertical support, 17, on which the rocker arm fulcrums, to bring as slight strain and stress, as conveniently can be, 10 on the retaining and releasing pin 19, hereinafter more fully described, which pin 19, when made of fusible material is somewhat delicate in nature. It is obvious as shown 15 in Fig. 4, that owing to the leverage exerted upon the rocker arm 16, by reason of the tension of the spring which operates the valve 23, the fusible pin 19, is subjected to greatly reduced strain. That is, owing to 20 the fact that the distance between the pin of the member 25, and the pivotal point p , as against the distance between the pivotal point p , and the fusible pin 19, are about 1 to 2 respectively, and therefore if the spring 25 exerts a pressure, for example of 5 pounds, the consequent strain upon the fusible pin 19, would be one-half said pressure. The horizontal support, 18, is provided at its outer end with an engagement recess, 29, to receive the end of the pin, 19. For strength and to avoid possible looseness or play of the parts and to resist the effect of heat or fire, the vertical support, 17, and the horizontal support, 18, preferably are made integral with the cap on the valve case. The horizontal support, 18, is provided with a branch, 30, at right angles thereto, to which is pivotally secured a tripping arm, 31, Figs. 5 and 6.

30 35 The retaining and releasing pin 19, is rigidly secured at one end to the inner end of the tripping arm, 31, and operates therewith, the tripping arm 31, and the pin 19, being substantially horizontal when the pin 40 is in retaining position. The outer end of the pin, 19, is engageable with the outer edge of the vertically extending portion, 28, of the rocker arm when said arm is locked, and the pin 19, at the same time engages in 45 the recess 29, of the support 18, when the pin 19, and the tripping arm, 31, as well, are in position for retaining the rocker arm locked. The pin 19, is tapered toward its end where it engages in the recess, 29, of 50 the support 18, but not tapered enough to prevent effective engagement in the recess, 29. The pin 19, preferably is made of fusible material, that is, of such material as readily to fuse or melt under heat and yet 55 be sufficiently strong for retaining purposes. Such fusible quality, however, relates only to the automatically operative feature of my invention, and where such feature of my device is not necessary or desirable, the pin, 60 19, may be of any suitable metal or material.

65 The branch 30, of my device may be, and preferably is, provided with a member, 32, having detent recesses 33, engaging detent projections 33', at the adjacent end of the tripping arm 31, the intention being to hold

by means of a spring the arm 31, in a horizontal position and prevent tendency, if any there be, of the pin 19, to loosen in its locking engagement. The tripping arm 31, has at its outer end a hole or other suitable arrangement for attaching thereto the hand-operating means for shutting off my device. The valve, 15, is provided with packing, 34, (Fig. 7) to render it fluid tight. All the parts or elements of my device, including the packing 34, of the valve, are made of non-combustible material, the pin, 19, being excepted when my device is automatically operative.

70 The form of my device, Figs. 9 and 10, is intended to cut off the flow of electricity in its passage from the source of supply to the point of use, a main throw off or cut out switch through which the electricity passes here being considered as the point of use for 75 purposes of illustration and description.

75 The form of my device, Figs. 9 and 10, is used in association with a main cut-out switch S, and comprises in its primary elements or parts a wall block or plate, 35, a bracket or plate 36, attached to the block or plate 35, having at one end a lock-post 37, an intermediate arm supporting post 38, a spring and contact member 39, a swinging arm 40, and a retaining and releasing pin 41. The lock-post 37, has at its outer end a longitudinal slot 42, to receive the adjacent end of the swinging arm 40, when the arm is moving outwardly, and an extending head 43, with an engagement recess 44, 100 therein, to receive one end of the pin 41. The arm supporting post, 38, is provided at its outer end with a rectangular branch-head 45, to the under side of which the swinging arm 40 is pivoted to permit the 105 arm to swing radially. The arm supporting post 38 may have a hole 46, therethrough for passage of a wire, chain or other flexible member for shutting off my device by hand. The spring and contact member 39, consists of a case 47, preferably cylindrical, attached to or forming part of the bracket or plate 36, and receiving slidably a stem 48, having a rectangular branch head 49, with the under side of which the outer end of the swinging arm 40 engages and by contact therewith is not permitted to swing farther inward. A spring, 50, embraces the case 47, and the stem 48, the spring being seated on the base, 49' and bearing against the rear of 110 the branch head 49, with a tendency to force the branch-head and stem outward, but not sufficiently so to withdraw the stem entirely from the case 47. A maul-head 51, is pivotally attached to the base block or 115 plate 35, adjacent to and below the lock-post 37, and the retaining and releasing pin 41, is secured thereto to operate therewith. The maul-head 51 is provided with a curved 120 tripping arm 52, so arranged relative to the 125

pin 41, that upward strain on the tripping arm will release the pin 41, from locking or retaining position. A member 53, substantially similar to the member 32, is provided to engage the maul-head 51. The retaining and releasing pin 41, is similar to the pin 19, of the main form of my invention.

My device is provided with what, for purposes of description and claim, I term operation terminals, which may be local operation terminals or distant operation terminals. The local operation terminal, for instance, is determined by the ring R, Fig. 1, or other suitable pull member, located adjacent to my device, as in C as indicating the basement of a building, and connected to my device by a chain or other suitable means to shut off flow. The distant operation terminal is determined by a suitable pull member 54, located in A as indicating the second story of a building and distant from my device, or by a pull member, 55, located in the exterior wall of a building or structure and accessible from the outside, in that respect being distant from my device, as it is apparent that, although the member 55, is shown near my device it may be placed in a vestibule, outer wall, or any suitable position distant from my device but accessible from the outside of a building. The importance of such terminals is realized when it is considered that many cities and towns have legally appointed persons whose first duty, in case of fire, is to shut off the flow of gas, electricity or water from the burning building, which by my device can be done readily, and without danger.

The means, such as wire or chain, connecting the distant terminals with the tripping arm 31, or 52 of my device, as the case may be, may be led through pipes or conduits either through or on the walls of buildings or structures, or any other suitable conducting means may be used. The local operation terminal is a ring R, or other suitable operation member adjacent to my device; the interior distant operation terminal is a pull member 54 or other suitable operation member located on an upper story, and the exterior distant operation terminal is a pull member, 55, or other suitable operation member located in the vestibule or exterior wall of a building and suitably accessible, but protected from intermeddlers. The operation of my hand operated and automatic cut-off device is as follows:

The rocker arm 16, Figs. 4 and 5, is drawn down to unseat the valve 23, and locked in position by engagement of the pin 19, with it and in the recess 29 in the horizontal support 18, the horizontal support and recess thus providing a detaining means, the valve being held open and flow permitted. Upward strain upon the tripping arm 31, releases the

pin 19 and permits the automatic reseating of the valve 23, and flow is shut off. In automatic operation fusing or melting of the pin 19, releases the rocker arm 16, and shuts off flow through the valve. In such case a new fusible pin, 19, is required to reset the valve for flow, but for temporary purposes a nail or piece of wire may be used instead of the fusible pin 19, but in such case the device, while hand operable, will not be automatically operative until a new fusible pin is provided.

In operation of the form of my device Figs. 9 and 10, the pin 41, engaging the inner end of the swinging arm 40, and in the recess 44, of the lock-post 37, holds the swinging arm in inoperable contact with the throw handle 56, of the switch S, and compresses the spring 48, and permits flow, the lock-post 37, providing a means for detaining the swinging arm 40. Release of the pin, 41, by upward strain on the tripping arm 52, or by fusing of the pin 41, relieves the tension of the spring 48. The outer end of the swinging arm 40, is forced forward and with it the switch handle 56, and the circuit is broken and the flow of electricity shut off. All the parts or elements of this form of my device are made of non-combustible material, the pin, 41, being excepted when my device is automatically operative.

I claim:

1. A cut-off device located between the source of supply and the point of use and comprising, a cut-off for permitting or preventing flow, an oscillating member for operating the cut-off, immobile detaining means for the oscillating member, a swinging member, a pin carried by said swinging member and movable therewith in a circular path and engageable with the immobile detaining means and engageable with said oscillating member to retain the oscillating member in detained position for permitting flow, and means for operating the swinging member to move said pin for releasing the oscillating member from said detained position to operate the cut-off to prevent flow.

2. A cut-off device located between the source of supply and the point of use and comprising, a cut-off for permitting or preventing flow, an oscillating member for operating the cut-off, a fixed member provided with a recess, said oscillating member being arranged for movement to bring one end thereof substantially at right angles to said fixed member at a point adjacent to said recess, a swinging member, a pin carried by said swinging member and movable therewith in a circular path and engageable in said recess and engageable with said end of the oscillating member when the oscillating member is in said adjacent position to retain the oscillating member in detained po-

sition for permitting flow, and means for operating the swinging member to move said pin for releasing the oscillating member from said detained position to operate 5 the cut-off to prevent flow.

3. A cut-off device located between the source of supply and the point of use and comprising a cut-off for permitting or preventing flow, an oscillating member for 10 operating the cut-off, a fixed member having a recess formed therein, said oscillating member being arranged for movement to bring one end thereof substantially at right angles to said fixed member at point 15 adjacent to said recess, a swinging member, a pin carried by said swinging member and movable therewith on the axis of the swinging member and engageable in said recess and engageable with said end of the 20 oscillating member when the oscillating member is in said adjacent position to retain the oscillating member in detained position for permitting flow, and means for operating the swinging member to move said pin 25 for releasing the oscillating member from said detained position to operate the cut-off to prevent flow.

4. A cut-off device located between the source of supply and the point of use and 30 comprising, a cut-off for permitting or preventing flow, an oscillating member for operating the cut-off, detaining means for the oscillating member, means comprising a fusible pin, said fusible pin being engageable 35 with said detaining means and engageable with said oscillating member to retain the oscillating member in detained position for permitting flow, said oscillating member being releasable by fusing of said pin from 40 said detained position to operate the cut-off to prevent flow.

5. A cut-off device located between the source of supply and the point of use and comprising, a cut-off for permitting or preventing flow, an oscillating member for 45 operating the cut-off, detaining means for the oscillating member provided with a recess, means comprising a fusible pin, said pin being engageable in said recess and engageable with said oscillating member to retain the oscillating member in detained position for permitting flow, said oscillating member being releasable by fusing of said pin from 50 said detained position to operate the cut-off to prevent flow.

6. A cut-off device located between the source of supply and the point of use and comprising, with means for operative support of the parts, a cut-off for permitting or preventing flow, an oscillating member for 60 operating the cut-off, a fixed support provided with a recess, a swinging member provided with a fusible pin, said pin being engageable in said recess of the fixed support and engageable with said oscillating 65

member to retain the oscillating member in position for permitting flow, and being releasable by fusing from said engagement for releasing the oscillating member to operate 70 the cut-off to prevent flow.

7. A cut-off device located between the source of supply and the point of use, and comprising a valve case, a valve in said case provided with an extended stem, a rocker member operatively supported and engaging said valve stem for operating the valve to permit or to prevent flow, a support provided with a recess at an end thereof, a tripping arm operatively supported and provided with a fusible pin for engaging 80 said recess in said support and for engaging said rocker member for normally retaining the rocker member in position to permit flow through said valve; said pin being releasable from said recess by fusing 85 to release said rocker member for operating said valve to prevent flow therethrough.

8. A cut-off device comprising a valve case having a source of supply inlet and a point of use outlet and having a vertical 90 support and a horizontal support rigidly fixed on the case at the upper end thereof, a horizontal support having a recess near the outer end, a valve in said case and having a stem extended through the case, said 95 stem having a slot and a pin for the slot at the upper end, a rocker arm pivoted on said vertical support and having a head engaging in the slot of the valve stem and a recess in the head engaging said pin, and having a 100 downwardly extending portion terminating adjacent to and below the horizontal support on the valve case, and a pin operatively supported and engageable with the edge of the downwardly extending portion of the 105 rocker arm and engageable in the recess in the horizontal support to retain the rocker arm in position for unseating the valve, said pin being adapted to release the rocker arm and permit the valve to seat. 110

9. A cut-off device comprising a valve case having a source of supply inlet and a point of use outlet and having a vertical support and a horizontal support rigidly fixed on the case at the upper end thereof, the horizontal support having a recess near the outer end, a spring actuated valve in said case having a stem extended through the case, said stem having a vertical slot and a pin for the slot at the upper end, a rocker arm pivoted on 120 said vertical support and having a head engaging in the slot of the valve stem and a recess in the head engaging said pin, and having a downwardly extending portion terminating adjacent to and below the horizontal support on the valve case, a pin operatively supported and engageable with the edge of the downwardly extending portion of the 125 rocker arm and engageable in the recess in the horizontal support to retain the rocker 130

arm in position to unseat the valve, said pin being adapted by fusing to release the rocker arm and permit the valve to seat.

10. A cut-off device comprising a valve
5 case having a source of supply inlet and a point of use outlet and having a vertical support and a horizontal support rigidly fixed on the case at the upper end thereof, the horizontal support having a transverse
10 recess near the outer end, a spring actuated valve in said case having a stem extended through the case, said stem having a vertical slot and a transverse pin for the slot at the upper end, a rocker arm pivoted on said vertical support and having a head engaging in the slot of the valve stem and a recess in the head engaging said transverse pin, and having a downwardly extending portion terminating adjacent to and slightly below the horizontal support on the valve case, an arm pivoted on said horizontal support having an oppositely extending pin operating there-
15 with and engageable with the outer edge of the downwardly extending portion of the rocker arm and engageable in said recess in the horizontal support to retain the rocker arm in position for unseating the valve, said pivoted arm having detent projections at its inner end, a spring actuated detent having recesses engaging the before mentioned projections, and means for operating said pivoted arm to release the rocker arm and permit the valve to seat. 70 75 80 85

25 provided in said horizontal support, an extending pin operating therewith and engageable with the outer edge of the downwardly extending portion of the rocker arm and engageable in said recess in the horizontal support to retain the rocker arm in position for unseating the valve, and means for operating the pivoted arm to release the rocker arm and permit the valve to seat.

30 11. A cut-off device comprising a valve case having a source of supply inlet and a point of use outlet and having a vertical support and a horizontal support rigidly fixed on the case at the upper end thereof, the horizontal support having a transverse recess near the outer end, a spring actuated valve in said case having a stem extending through the case, said stem having a trans-

13. A cut-off device comprising a cut-off for permitting or preventing flow, an oscillating member for operating the cut-off, a fixed member for providing detaining means for the oscillating member, a swinging member provided with a bore, a pin received in said bore and movable with the swinging member on the axis of the swinging member, said pin being engageable with said detaining means and engageable with said oscillating member to retain the oscillating member in detained position for permitting flow, and means for operating the swinging member to move said pin for releasing the oscillating member from said detained position to operate the cut-off to prevent flow.

30 11. A cut-off device comprising a valve case having a source of supply inlet and a point of use outlet and having a vertical support and a horizontal support rigidly fixed on the case at the upper end thereof, 95
35 the horizontal support having a transverse recess near the outer end, a spring actuated valve in said case having a stem extending through the case, said stem having a trans- 100
40 verse slot and a transverse pin for the slot at the upper end, a rocker arm pivoted on said vertical support and having a head eng- 105
45 gaging in the slot of the valve stem and a recess in the head engaging said transverse pin, and having a downwardly extending portion terminating adjacent to and slightly below the horizontal support on the valve case, an arm pivoted on said horizontal support having an extending fusible pin operating therewith and engageable with the 110
50 outer edge of the downwardly extending portion of the rocker arm and engageable in said recess in the horizontal support to retain the rocker arm in position for unseating the valve, and means for operating said piv- 115
55 oted arm to release the rocker arm and permit the valve to seat. 120

30 said pin being engageable with said detain- 95
35 ing means and engageable with said oscillating member to retain the oscillating member in detained position for permit- 100
40 ting flow, and means for operating the swinging member to move said pin for re- 105
45 leasing the oscillating member from said de- 110
50 tained position to operate the cut-off to pre- 115
55 vent flow.

14. A cut-off device comprising, a cut-off for permitting or preventing flow, an oscil- 105
15 lating member for operating the cut-off, a fixed member for providing detaining means for the oscillating member, a swinging mem- 110
20 ber provided with a bore, and a pin received in said bore and movable with the swinging mem- 115
25 ber on the axis of the swinging member, said pin being engageable with said detain- 120
30 ing means and engageable with said oscillat- 125
35 ing member to retain the oscillating member in detained position for permitting flow, and being fusible for releasing the oscillating member from said detained position.

15. In combination, a cut-off, detaining means, a pivoted member, a pin arranged transversely to the pivot of said member and movable with said member in a circular path 130

12. A cut-off device comprising a valve case having a source of supply inlet and a point of use outlet and having a vertical support and a horizontal support rigidly fixed on the case at the upper end thereof, the horizontal support having a transverse recess near the outer end, a spring actuated valve in said case having a stem extending through the case, said stem having a vertical 60 65 125 130

for engagement with said detaining means transversely thereto, and an operating member for the cut-off arranged to engage said pin transversely thereto between said detaining means and said pivoted member when said pin is in engagement with said detaining means for retaining the operating member in detained position, said operating member being releasable from said de-

tained position by movement of said pivoted member to release said pin from transverse engagement with said detaining means.

16. In combination, a cut-off, detaining means, a pivoted member, a pin arranged transversely to the pivot of said member and movable with said member in a circular path and engageable with said detaining means transversely thereto, and an operating member for the cut-off arranged to engage said pin transversely thereto between said detaining means and said pivoted member when said pin is in engagement with said detaining means for retaining the operating member in detained position, said pin being fusible for releasing the operating member from said detained position.

17. In combination, a cut-off, a fixed member having a recess formed therein, a pivoted member, a pin arranged transversely to the pivot of said member and movable on said pivot with said member and engageable with said fixed member transversely thereto and in said recess, and an operating member for the cut-off arranged to engage said pin transversely thereto at a point between said fixed member and said pivoted mem-

ber when said pin is in engagement with said fixed member for retaining the operating member in detained position, said operating member being releasable from said detained position by movement of said pivoted member to release said pin from transverse engagement with said fixed member.

18. In combination, a cut-off, a fixed member having a recess formed therein, a pivoted member, a pin arranged transversely to the pivot of said member and movable on said pivot with said member and engageable with said fixed member transversely thereto and in said recess, and an operating member for the cut-off arranged to engage said pin transversely thereto at a point between said fixed member and said pivoted member when said pin is in engagement with said fixed member for retaining the operating member in detained position, said pin being fusible for releasing the operating member from said detained position.
